UNITED STATES PATENT OFFICE.

HENRY T. RUSSELL, OF CHICAGO, ILLINOIS.

SPIKE.

SPECIFICATION forming part of Letters Patent No. 278,604, dated May 29, 1883.
Application filed February 23, 1883. (No model.)

To all whom it may concern:

Be it known that I, HENRY T. RUSSELL, a citizen of the United States, residing at Chicago, Illinois, have invented new and useful Improvements in Railroad-Spikes, of which the following is a specification.

My invention relates to certain new and useful improvements in railroad-spikes. It has for its object economy of material used coupled with increased strength and great facility of entry into wood; and, with these objects in view, my invention consists of a railroad-spike having a suitable head and square shank for a suitable distance below the head, and with the remainder of the shank having its four corners grooved out, leaving a straight vertical rib, and terminating in a chisel-point, as will be hereinafter fully set forth, and specifically claimed.

In order that those skilled may fully understand my invention, I will proceed to describe the construction and advantages of my improved spike, referring by letters to the accompanying drawings, in which—

Figure 1 is a plan view of a spike embodying my invention; Fig. 2, a similar view at right angles to that shown at Fig. 1; Fig. 3, a cross-section, taken at the line *x x* of Fig. 2; and Fig. 4, a plan view of a rod, showing the method of forming the spikes continuously from a square rod or blank.

Similar letters denote like parts in the several figures.

A represents the head of the spike, which may be of any form, but preferably that shown. The shank below the head for a suitable distance is square, as shown at *B*, to give full strength at that point usually subjected to the greatest strain; and from the squared portion *B* down to the point the four corners are concaved, as seen at *C*, leaving the four vertical ribs, *D*, the two side ones of which extend to the extreme point, while the front and rear ones terminate in the bevels *E*, which produce a chisel-point, as clearly seen at Figs. 1 and 2. The corners being concaved leaves the body in cross-section of the geometrical form shown in Fig. 3. The upper ends of the concave *C* decrease in depth and vanish into the sharp or angular corners of the square portion *B* of the shank to avoid a too sudden or abrupt enlargement.

By reference to Fig. 3 it will be seen that the contact-surface of the spike is much larger than it would be in an ordinary square-shanked spike, that the holding capacity is proportionately increased, and that the ribs *D*, being at right angles to each other and in the same planes with the sides of the square portion *B*, serve to render the entrance of the spike easy and at the same time secure it, in its entering movement against any twisting or deflection, so that being started properly with reference to the desired location of the square portion *B*, said portion will be suitably guided and delivered in an obvious manner.

In the manufacture of my improved spikes they may be formed from a continuous rod between rotary dies or rollers, so constructed as to produce the points, ribs, concaves, and a square portion, which latter, being longer than the portions *B* in a finished spike, may be readily upset to form the head, as illustrated at Fig. 3, all of which will be readily understood by those familiar with the art of forming articles of iron from a continuous rod.

I am aware that it has been suggested to make spikes of various forms in cross-section, and that spikes have been made square in cross-section, with vertical grooves formed in the flat sides of the spike, and do not wish to claim, broadly, the idea of grooving a spike longitudinally; but

What I do claim as new, and desire to secure by Letters Patent, is—

1. A spike provided with a suitable head, and short square portion below the same, and having the four corners below said square portion concaved, with intermediate vertical ribs on opposite sides, substantially as and for the purposes hereinbefore set forth.

2. The ribs *D* on the sides of the spike continued to the extreme point, while the ribs on the front and back portions terminate in the bevels *E*, whereby a chisel-point is formed, substantially as shown and described.

In witness whereof I have hereunto set my hand in the presence of two subscribing witnesses.

HENRY T. RUSSELL.
